C. A. ROBERTS. OF WEST MERIDEN, CONNECTICUT.

Letters Patent No. 91,166, dated June 8, 1869; antedated April 27, 1869.

IMPROVEMENT IN ATTACHING PEN-RACKS TO INKSTANDS.

The Schedule referred to in these Letters Patent and making part of the same.

To all whom it may concern:

Be it known that I, C. A. ROBERTS, of West Meriden, in the county of New Haven, and State of Connecticut, have invented a new Improvement in Pen-Rack for Inkstands; and I do hereby declare the following, when taken in connection with the accompanying drawings, and the letters of reference marked thereon, to be a full, clear, and exact description of the same, and which said drawings constitute part of this specification, and represent, in—

Figure 1, a perspective view, and in

Figure 2, a top view.

This invention relates to an improvement in racks for holding writing-pens, the object being to combine a rack with the inkstand, so that the rack may be rigidly attached thereto, but constructed so as to be adjustable to different-sized stands; and

The invention consists in forming the base of the stand so as to partially surround the neck, and the base provided upon one side with an inward projection, and upon the opposite side with an adjustable binding-screw, the said projection and screw acting together, to rigidly bind the stand.

In order to the clear understanding of my invention, I will fully describe the same as illustrated in the accompanying drawings.

A is the base of the stand, formed with a circular recess, B, so as to extend more than half way around the neck of the inkstand, the inner edge provided upon one side with a projection, *a*, and upon the opposite side with a set-screw, *d*, so that when the said neck is set around the base of the stand, as denoted in fig. 2, (the neck of the stand being denoted in red,) the projection *a* grasps the neck in front of a centre-line, and thus tends to draw the base on, and firmly secure it to the neck, taking a bearing at the projection, and at the screw, and also at the back.

From the base, A, standards C extend upward, of any desirable form or configuration, upon the projections of which the pens are placed.

What I claim as my invention, and desire to secure by Letters Patent, is—

A pen-rack, having the base constructed with the projection *a* and set-screw *d*, so as to be arranged upon and secured to the inkstand, in the manner and as herein set forth.

C. A. ROBERTS.
